DROP PIT APPARATUS

Louis D. Holmes, Harvey, Ill., assignor to Whiting Corporation, Harvey, Ill., a corporation of Illinois

Application May 1, 1936, Serial No. 77,319

12 Claims. (Cl. 104—33)

The invention relates to drop pit mechanism for handling wheels and trucks used in railway equipment. One object of the invention is to provide a combination or sectional drop-table of this type in which the inner section is adapted to travel on the lifting mechanism crosswise of the pit so that its load, after being transferred in the pit to another track, can be shifted to either side 5 of the pit and onto the floor track at either side of the pit.

Another object of the invention is to provide a combination or sectional drop-table of this type with means for locking the inner section 15 against the side wall of the pit and protecting it against tipping while transferring the load from said section. This object is attained by providing locking bars on the inner section which engage pockets in the side walls of the pit. 20 Another object of the invention is to provide a combination or sectional drop-table of this type in which the inner table section is locked in its correct position to pass vertically into the opening in the outer table section. This object is attained primarily by means carried by the lifting 25 carriage for latching the inner table section in such position.

Another object of the invention is to provide a combination or sectional drop-table in which retractible engaging members, such as wheels, are provided for the inner section, so that both sections of the table can be directly engaged and lifted or lowered by the carriage of the lifting mechanism. This object is attained by providing wheels which act as spacers engageable 30 by the lifting carriage and can be retracted so that the carriage will simultaneously and directly engage both sections of the drop-table.

Another object of the invention is to provide improved lifting mechanism for the drop-table in which the screw-posts for shifting the lifting carriage are rotatable and have their lower ends confined in housings on which are mounted 40 standards for holding the upper ends of the posts.

Another object of the invention is to provide a drop-table which is efficient in operation and facilitates the handling of wheels and trucks in drop-pits.

Other objects of the invention will appear from the detailed description.

The invention consists in the several novel features which are hereinafter set forth and are more particularly defined by claims at the conclusion hereof.

In the drawings:

Fig. 1 is a perspective of a drop-table embodying the invention.

Fig. 2 is a transverse section of the drop-table and the lifting mechanism for the table, the 5 lifting carriage of said mechanism being shown as engaging the central drop-table section for independently raising or lowering it.

Fig. 3 is a section of the drop-table and lifting mechanism on line 3—3 of Fig. 2. 10

Fig. 4 is a section illustrating the central drop-table section on the lifting carriage and in position to discharge a pair of wheels onto or receive them from a track at floor level, at one side of the pit. 15

Fig. 5 is a horizontal section on line 5—5 of Fig. 2.

Fig. 6 is a vertical longitudinal section illustrating both sections of the drop table engaged directly by the lifting carriage, for conjointly 20 raising or lowering both table-sections.

Fig. 7 is a vertical section on line 7—7 of Fig. 5.

Fig. 8 is a detail vertical section illustrating one of the spacers on the central drop-table section in position to be engaged by the lifting 25 mechanism.

Fig. 9 is a similar section illustrating the spacer retracted and the lifting carriage directly engaging said section.

The invention is exemplified with a shop installation which comprises a series of tracks in any suitable number on the floor of the shop with rails *b* terminating at the sides of a transverse pit *a* which intersects the tracks, and a drop-table structure provided with rail-sections for 30 bridging the pit. A trolley carrying the lifting mechanism is adapted to travel on rails *c* on the bottom of the pit, and comprises a truck which is composed of side beams *d* and cross beams *d'* rigidly secured together to form a frame for 35 supporting the lifting mechanism and wheels *d*² adapted to travel on the rails *c*. A lever *d*³ carries a two-way pawl for engaging a toothed wheel *d*⁵ on the cross axle for one pair of the wheels *d*² so that the trolley and lifting mechanism can be propelled in the pit. A table-engaging lifting carriage *e* comprises pairs of cross beams *e'* rigidly connected by longitudinal beams *e*² to form a rigid vertically movable table-lifting structure. A bracket *e*⁴ is fixed to, and extends 40 between two of the beams *e'* at each corner of the carriage *e* and is provided with a socket *e*⁵ (Fig. 7) to receive and non-rotatively hold, a nut *e*⁶. The mechanism for raising and lowering the carriage *e* comprises a series of four screw-posts 45

50

55

55

f, the lower ends of which are journaled in bearings in the lower section *f'* of a gear-housing which is fixedly secured between the longitudinal beams *d* of the trolley frame. The posts *f* are threaded to the nuts *e*⁶ which are non-rotatively held in brackets *e*⁴ and support the carriage *e*. Rotation of the posts will raise and lower the nuts and the carriage *e*. The upper ends of screw-posts *f* are journaled in bearings *f*² which are provided at the upper ends of I-beam standards *f*³. The lower ends of standards *f*³ are fixedly secured to the cover sections which are secured to the housing sections. These standards, which are rigid with the trolley-frame, serve to rotatively support the screw-posts *f* and hold their upper ends against lateral displacement. The screw-posts *f* are operable by power to raise and lower the carriage *e* and the drop-table when it is superimposed on the carriage.

20 The power mechanism comprises a bevelled gear *g* fixed to the lower end of each of the screw-posts and in the housing-section *f'*, an electric motor *g'* mounted on the trolley frame and connected to drive suitable speed-reducing gearing *g*², a shaft *g*³ driven by the speed-reducing gearing *g*², bevelled pinions *g*⁴ fixed to the ends of shaft *g*³ and meshing with the gears *g*² at one end of the trolley, bevelled pinions *g*⁵ meshing with the aforesaid gears, respectively, and fixed 30 to longitudinal shafts *g*⁶, and bevelled pinions *g*⁷ which are driven by shafts *g*⁶ respectively, and mesh with bevelled gears *g* on the screw-posts *f* at the other end of the trolley. The motor *g'* is of the reversible type so that the gearing operated thereby may be driven to rotate the screw-posts *f* in opposite directions to raise or lower the lifting carriage *e*. The sections *f'*, which are fixed to the trolley frame, and the section *f*⁴ to which the standards *f*³ are fixed, are shaped 40 to form housings for respectively enclosing the bevelled gears *g* and the bevelled pinions meshing therewith. These housings are adapted to retain lubricant and to exclude dust and dirt from the gears. A packing-ring *f*⁷ is provided 45 in each housing section *f*⁴ to prevent the escape of lubricant. This exemplifies a housing for the gearing for driving the screw-posts, which supports the standards *f*³ and retains lubricant for the gears and bearings for the gears and the 50 screw-posts. It also provides a construction which permits ready access to the gears because the sections *f*⁴ are readily removable with the standards from the housing sections *f'* which are fixed to the trolley frame.

55 The invention is exemplified in a drop-table which is composed of an outer section *h* and an inner section *k*. The pit *a* is of sufficient width to receive a complete engine trailer, tender or car truck. The entire drop-table is adapted 60 to bridge the pit, to receive such trucks when it is in its track-bridging position and to raise or lower such trucks when the table is superimposed on the lifting carriage *e*.

The outer table section is built up of side beams 65 *h'* of I-beam stock of sufficient length to extend across the pit and between the ends of the rails *b* which terminate at the sides of the pit, and cross-beams *h*², which are rigidly secured to the beams *h'* to form a rigid rectangular frame- 70 structure. The outer table section *h* has a rectangular opening at its center between the beams *h'* and *h*² and the inner table section *k* fits into said opening. Beyond each end of said rectangular opening the outer table section has a portion of 75 sufficient area to support a pair of wheels, and

these end portions are rigidly joined by the side beam *h'*. This opening is of sufficient area for dropping a pair of wheels between the wheels on the end portions of the outer section *h*. The inner table section *k* is composed of outer channel-beams *k*² and inner I-beams *k'*, which are rigidly connected together by cross-beams *k*³. This inner table section is adapted to extend into the central rectangular opening in the outer table section *h*, is of sufficient area to form a rigid 10 supporting section of the table for a pair of wheels. The ends of the outer table section *h* are provided with rail sections *h*⁵ and the inner table section *k* is provided with rail sections *k*⁶ which are aligned with the rails *b* on the floor 15 of the shop. These rail sections *h*⁵, *k*⁶, when the drop-table is supported at the floor or track level, complete the railway track over the pit and across the rail sections *b*. The outer table section *h* is supported in pit-bridging position by a 20 series of four bolts *20* which straddle, and are horizontally slidable on, the vertical webs of the side beams *h'* and are adapted to be projected into recesses *21* in the side walls of the pit. The bolts *20* at either side are slidable into and out of 25 operative position by a hand lever *23* which is fulcrumed in one of the beams *h'* and arms for shifting links *24* to which said bolts are connected. By means of these levers and bolts, the outer table section may be secured in track-bridging position while the inner table section is in, or is removed from, the outer table section. 30 The inner table section *k* is adapted to be latched to and supported by the outer table section and released therefrom for independent 35 vertical movement by a series of four bolts *26* which straddle and are slidably mounted on the longitudinal beams *k'* of table section *k* and are adapted to be projected so as to rest on the lower flanges of the inner cross-beams *h*² of the outer 40 table section *h* to support the inner section from the outer table section at track-bridging level. These four bolts are conjointly shiftable to project them into and out of said beams *h*² by a hand-lever *27* which is fixed to a cross-shaft *28*, 45 which is journaled in and extends through the longitudinal beams *k*², and carries arms for shifting links *29* which are connected to all of the bolts *26*, respectively. This exemplifies means for releasably latching the inner table section 50 to the outer table section, so that the two sections may be supported to bridge the pit or for conjoint vertical movement, or released for independent vertical movement of the inner table section. There is sufficient clearance between 55 the upper flanges of beams *h*² and bolts *26* to permit the inner table section to be raised slightly, to free the bolts for retraction. There is also sufficient clearance in sockets *21* above bolts *20* to permit the outer table section to be raised to 60 free said bolts for retraction.

The lifting carriage *e* is provided with a pair of longitudinal rails *30* which are fixed to the top of beams *e'* and underlie the table sections and are preferably under or in the vertical planes of 65 the rail sections on the table sections. These rails *30*, when the carriage is lifted, raise the entire table for raising or lowering, and directly engage the cross-beams *h*² of the outer table section and the cross-beams *k*³ of the inner table 70 section. The carriage will then directly and conjointly or unitarily raise or lower the entire drop-table and the load thereon. This makes it possible to drop an entire engine trailer, tender, or car truck into the pit. 75

The outer table section h is preferably provided with flooring over the beams h^2 between rail sections h^5 and between said rail sections and beams h' to cover the spaces between the beams. Openings h^9 are formed in the flooring to permit the standards f^3 and screw-posts f to pass upwardly through the outer table section in lowering said section. The inner table-section is also provided with flooring between beams k' and also between rails k^6 and beams k^2 to cover the spaces in said table section.

When the outer table section h is locked in track-bridging position and the bolts 26 for supporting the inner table section k from the outer section, are retracted, and the inner table section is released, the latter, when superposed on the carriage e , may be dropped, independently of the outer table section. This makes it possible to lower one of several pairs of wheels of a truck over the table when that pair is spotted over the inner table section, while other pairs of adjacent wheels are resting on the ends of the outer table section.

In practice, it is sometimes necessary to raise one of several pairs of wheels resting on the drop-table for making repairs or for disconnecting that pair from the truck preparatory to dropping it into the pit. For this purpose, the wheels to be raised are spotted on the inner table section k and retractable means are provided for causing the lifting-carriage e to engage the inner table section and lift it above track-level independently of the outer table section. This means comprises two pairs of wheels 32 which are journaled in brackets 33 . These brackets are pivotally supported so they can be swung to bear against the under side of the longitudinal beams k' and are fixed to shafts 34 which are journaled in brackets 35 which are fixed to beams k' . The rollers 32 are adapted to be engaged by the tracks 30 on the lifting-carriage and serve as spacers between the inner table section k and the carriage e for raising said section while the outer table section remains at pit-bridging level. When the rollers 32 and brackets 33 are swung out of the path of the lifting carriage e , the rails 30 will be clear to engage both the outer and inner sections of the table for conjoint shift thereof. The rollers 32 and brackets 33 are shiftable into and out of operative position by mechanism comprising gear-wheels 37 fixed to shafts 34 , worm-wheels 38 fixed to a cross-shaft 39 , which is journaled in brackets which are fixed to beams k' , a sprocket-wheel 41 fixed to one end of shaft 39 , and a pendant-chain 42 whereby the sprocket 41 may be rotated manually by an operator in the pit. When the brackets 33 with rollers 32 are swung downwardly and laterally, as shown in Fig. 9, the rails 30 on the lifting-carriage e will clear the rollers 32 and brackets 33 and permit said rails to directly engage the cross-beams of both of the table sections. When the rollers are swung under the beams k' , as shown in Fig. 8, rails 30 will engage the rollers, so that the carriage e will lift the inner table section and the single pair of wheels thereon independently of the outer table section and the wheels on that section.

When the inner table section with a pair of wheels thereon has been dropped from the truck, that section will be supported on the lifting carriage with rollers 32 engaging rails 30 . In order to retain the inner table section against longitudinal movement and aligned with the rectangular opening in the outer table section, a latching device (Fig. 8) is provided, which con-

sists of a plunger 44 which is mounted for vertical sliding movement in one of the beams of lifting carriage e and is adapted to enter a socket 45 in one of the roller-carrying brackets 33 . A spring 46 holds the plunger 44 normally raised. To release the plunger from said bracket 33 , the operator will step on the head 47 fixed to the plunger. Normally, the plunger projects into the path of said bracket 33 when it is swung under the beam k' , so that when the inner table section is rolled over the rails 30 on the lifting carriage, the plunger 44 will automatically snap into socket 45 , when said section reaches its central position on the lifting-carriage where it will be aligned with the opening in the outer table section.

The purpose of providing rollers 32 for carrying the inner table section k is to permit that section to be shifted to either side of the pit after the pair of wheels has been dropped from the truck, moved in the pit, raised to floor level, and transferred to another track in the shop. When the bolt 44 is released, the table section k may be rolled on rails 30 of the carriage e to either side of the pit to bring the ends of the rail sections k^6 close to the ends of the rails b of the track to which the wheels are to be transferred. When the inner table section has been thus shifted to discharge the pair of wheels, two of the bolts 26 , which are normally used to support the inner table section k from the outer section h , may be shifted through lever 27 , to project said bolts into sockets in beams built in the side walls of the pit. These sockets are provided with lugs 49 to interfit with depending ribs on the ends of bolts 26 so that the inner table section will be locked to the pit during the transfer of the wheels to the adjacent track. This exemplifies an inner table section which is shiftable from its central position on the lifting carriage to either side of the pit for transferring the load and locking the section to the pit during the transfer, and preventing it from tipping.

The operation will be as follows: Normally both sections h , k of the table are locked at track level, the outer rectangular section h being supported by bolts 26 from the pit walls and the inner table section being supported by the bolts 26 from the outer table section. When a truck which is to be removed from the rolling stock has been spotted on the entire table and is to be dropped, the lifting carriage e is raised so its rails 30 will directly engage the cross-beams of both of the drop table sections. When the bolts 26 are released, the truck may be lifted slightly above track level, so it can be disconnected from the car or locomotive. When disconnected, the lifting carriage e may be lowered into the pit, so the trolley with the entire table can be transferred in the pit, the carriage e raised to floor level at another track, and the wheels rolled off the table. When it is desired to remove a single pair of wheels from the rolling stock, the wheels to be removed are spotted on the inner table section k while the adjacent wheels are supported on the contiguous end portions of the outer table section h . While the lifting carriage e is lowered away from the table, the operator will manipulate chain 42 to swing the brackets 33 and rollers 32 under the beams k' of the inner table section and over the rails 30 on the lifting carriage e . When carriage e is raised, its rails 30 will engage rollers 32 . The bolts 26 will then be retracted through lever 27 to release the inner table section k from the section h . If desired or necessary, the lifting carriage can then be

raised a sufficient distance independently of the outer section to lift the pair of wheels on the inner section so they can be detached from the truck or repaired. If the pair of wheels is to be replaced or removed for repair, the carriage *e* is lowered so the wheels will clear the side-beams of the outer table section. The trolley with the inner table section thereon can then be shifted to a vacant track where the lifting carriage *e* and its load will be raised while the section *k* is aligned with the said track. During this operation, the table section *k* will be locked against movement on the lifting carriage by the spring-pressed plunger *44*. The operator will then release the plunger from bracket *33* and roll the wheels on table section *k* toward either side of the pit to bring the ends of the rail sections *k*⁶ close to the rails *c* of the track on the floor and will shift the bolts *27* to interlock with the lugs *59* in the contiguous pit wall so that the table section will be held against movement away from the wall and against tilting. The pair of wheels can then be rolled off the inner table section onto the track on the floor.

To replace the inner table section, it is first lifted slightly so its bolts *26* can be retracted by means of lever *27*. This section can then be rolled to the center of the lifting carriage *e* where it will be arrested in its central position by the spring plunger *44*. This section can then be dropped and transferred by the trolley into position so it can be lifted into the outer table section *h* and supported therein to complete the track across the pit.

The invention is not to be understood as restricted to the details set forth, since these may be modified within the scope of the appended claims, without departing from the spirit and scope of the invention.

Having thus described the invention, what I claim as new and desire to secure by Letters Patent is:

1. In drop pit apparatus, the combination in a drop table adapted to bridge a pit, of a plurality of sections, one of the sections being disposed within and adapted to be dropped independently of the other, means for supporting both ends of the outer table section from the walls of the pit, releasable supporting means between the sections, and rollers for the inner section to permit it to travel crosswise of the pit when supported on lifting mechanism, said rollers being movable under the inner sections for engagement by the lifting mechanism, for lifting the inner section above the outer section and into position to render both sections engageable by the lifting mechanism.
2. In drop pit apparatus, the combination in a drop table adapted to bridge a pit, of a plurality of sections, one of the sections being disposed within, and adapted to be dropped independently of the other, means for releasably supporting both ends of the outer section from the walls of the pit, releasable supporting means for the inner section between the sections, a lifting carriage provided with tracks, and rollers on the inner section movable into and out of position to be engaged by the tracks, the tracks being adapted to directly engage both table sections when the rollers are shifted out of position to be engaged by the tracks.
3. In drop pit apparatus, the combination in a drop table adapted to bridge a pit, of an outer section having end portions adapted to drop wheels and an inner section centrally disposed in

the outer section and adapted to drop a pair of wheels independently of the outer section, means for latching the outer section across the pit, means for releasably supporting the inner section from the outer section, wheels on the inner section to permit travel of the inner section crosswise of the pit when it is supported on lifting mechanism, and means for holding the inner section against crosswise movement of the pit on lifting mechanism when it is dropped from the outer section.

4. In drop pit apparatus, the combination in a drop table adapted to bridge a pit, of a plurality of sections, one of the sections being disposed within and adapted to be dropped independently of the other, means for supporting both ends of the outer table section from the walls of the pit, releasable supporting means between the sections, rollers for the inner section to permit it to travel crosswise of the pit when supported on lifting mechanism, and means for releasably latching the inner section in position to pass into the outer section.

5. In drop pit apparatus, the combination in a drop table adapted to bridge a pit, of a plurality of sections, one of the sections being disposed within and adapted to be dropped independently of the other, means for supporting both ends of the outer table section from the walls of the pit, releasable supporting means between the sections, rollers for the inner section to permit it to travel crosswise of the pit when supported on lifting mechanism, a lifting carriage, and means on the lifting carriage for releasably holding the inner section against such crosswise movement and in position to pass into the outer section.

6. In drop pit apparatus, the combination in a drop table adapted to bridge a pit, of a plurality of sections, one of the sections being disposed within, and adapted to be dropped independently of the other, means for supporting both ends of the outer table section from the walls of the pit, releasable supporting means for the inner section between the sections, rollers for the inner section to permit it to travel crosswise of the pit when supported on lifting mechanism, a lifting carriage provided with tracks for engaging the rollers, and means for directly latching the inner table section directly to one side of the pit when it is supported by the lifting carriage.

7. In drop pit apparatus, the combination in a drop table adapted to bridge a pit, of a plurality of sections, one of the sections being disposed within, and adapted to be dropped independently of the other, means for supporting both ends of the outer table section from the walls of the pit, releasable supporting means for the inner section between the sections, rollers for the inner section to permit it to travel crosswise of the pit when supported on lifting mechanism, a lifting carriage provided with tracks for engaging the rollers, and means for directly latching the inner table section directly to either side of the pit when it is supported by the lifting carriage.

8. In drop pit apparatus, the combination in a drop table adapted to bridge a pit, of a plurality of sections, one of the sections being disposed within, and adapted to be dropped independently of the other, means for releasably supporting both ends of the outer table section from the walls of the pit, releasable supporting means between the sections, a lifting carriage provided with tracks on which the inner section can travel

crosswise of the pit, spacing means for independently lifting the inner section, and means for directly latching the inner table section to the carriage and against crosswise travel when it is supported by the lifting carriage.

9. In drop pit apparatus, the combination of a drop table comprising a plurality of sections, one of which is adapted to be dropped either with, or independently of, the other, lifting and lowering mechanism for said table, means for releasably supporting the table from the walls of the pit, and rollers for the travel of the independently lowerable section transversely of the pit on table lifting and lowering mechanism.

10. In drop pit apparatus, the combination of a drop table comprising a plurality of sections, one of which is adapted to be dropped either with, or independently of, the other, lifting and lowering mechanism for said table, means for releasably supporting the table from the walls of the pit, and rollers mounted on the independently

lowerable section for travel transversely of the pit and on table lifting and lowering mechanism.

11. In drop pit apparatus, the combination of a drop table adapted to bridge the pit and comprising a plurality of sections, one of which can be dropped independently of the other, means for releasably supporting the table from the pit, a lifting carriage for the table, and rollers and tracks for the travel of the lowerable section on the carriage and transversely of the pit.

12. In drop pit apparatus, the combination of a drop table adapted to bridge the pit and comprising a plurality of sections, one of which can be dropped independently of the other, means for releasably supporting the table from the pit, rollers carried by the independently lowerable section, and a lifting carriage provided with tracks on which the rollers can travel on the carriage and transversely of the pit.

LOUIS D. HOLMES.

20
